Patented Apr. 4, 1967

207,315

BACK REST

Warren S. Radford, 12306 Miles Ave.,
Cleveland, Ohio 44105

Filed Aug. 26, 1965, Ser. No. 86,731

Term of patent 14 years

(Cl. D15—8)

FIG.1

FIG.5

FIG.6

FIG. 1 is a side view of a back rest embodying my new design;

FIG. 2 is a top plan view of the back rest;

FIG. 3 is an end view of the back rest as viewed from the left hand end of FIG. 2;

FIG. 4 is an end view of the back rest as viewed from the right hand end of FIG. 2;

FIG. 5 is a plan view of the back of the back rest; and

FIG. 6 is a perspective view of the back rest.

I claim:

The ornamental design for a back rest, as shown.
